UNITED STATES PATENT OFFICE

GEORGE JOHNSON, OF LOS ANGELES, CALIFORNIA

DESIGN FOR AN ASH TRAY

Application filed March 28, 1932. Serial No. 43,303. Term of patent 14 years.

To all whom it may concern:

Be it known that I, GEORGE JOHNSON, a citizen of the United States of America, residing at Los Angeles, in the county of Los Angeles and State of California, have invented a new, original, and ornamental Design for an Ash Tray, of which the following is a specification, reference being had to the accompanying drawings, forming a part thereof,

I claim:

The ornamental design for an ash tray as shown.

GEORGE JOHNSON.
